[57] ABSTRACT

Detergent mixtures comprising a) an alkylsulfonic acid deriving from a light petrol and containing a sulfonic acid group per 7 carbon atoms at most, b) a low-molecular oxalkylation product of a lower alkyl amine and c) a phosphate of alkanols of 4 to 8 carbon atoms are useful as wetting agents for alkaline baths.

5 Claims, No Drawings

WETTING AGENTS FOR ALKALINE BATHS

This is a continuation-in-part of our copending application Ser. No. 99,264, filed December 17, 1970, now U.S. Pat. No. 3,730,903 issued May 1, 1973 which in turn is a continuation-in-part of application Ser. No. 701,119 filed Jan. 29, 1968, now abandoned.

The present invention relates to surface active agents, especially to wetting agents for alkaline baths, in particular for mercerizing-and leaching baths.

The present wetting agents are mixtures containing a. alkyl sulfonic acids or their alkali metal salts having on an average one sulfonic acid group per 7 carbon atoms at most, deriving from light petrol boiling at 30°-80°C;

b. an alkyl dialkanolamine of the general formula

in which R represents an alkyl radical of 2 to 5 carbon atoms, n represents the integer 2 or 3 and m represents a number of 1 to 2 and

c. an ester of phosphoric acid and of alkanols of 4 to 8 carbon atoms, and if desired, further usual auxiliary agents.

It is already known from German Auslegeschrift No. 1,014,067 that high molecular weight aliphatic sulfonic acids containing more than one sulfonic acid group per molecule are used as wetting agent for mercerizing-and leaching baths.

Furthermore, it is known from German Pat. No. 955,857 that mixtures of alkyl sulfonates of 5 to 10 carbon atoms in the alkyl radical and alkyl sulfates, the alkyl radical of which containing 10-16 carbon atoms can be used as wetting agents for mercerizing baths. Additionally, in order to improve the solubility of the sulfonates in the mercerizing liquors, small amounts of aliphatic alcohols, amines, alkylamines, ether alcohols or naphthene acids can be used as auxiliary solvent.

It has been found that mixtures of a) aliphatic sulfonic acids deriving from light petrol containing on an average one sulfonic acid group per 7 carbon atoms or their alkali metal salts, b) lower alkyl dialkanolamines and c) phosphoric acid esters of alkanols of 4 to 8 carbon atoms for foam reduction, which may be partially saponified, are used as extremely active and clearly soluble wetting agents even in cold alkaline baths.

It was surprising and unforeseeable that the addition of the alkyl dialkanolamines to the mentioned alkyl sulfonic acids or their alkali metal salts leads to such active, clearly soluble wetting agents. The technical advantages of the wetting agent-mixtures to the process of the present invention are, for example, to be seen from the table shown further below. Especially advantageous in industrial use are the highly improved shrinkage values obtained with said mixtures.

Due to the phosphoric acid esters there are obtained mercerizing baths which are practically free of foam. This is especially advantageous when working on yarn mercerizing machines. To the mercerizing- or leaching baths prepared by using the mixtures of the present invention other surface active compounds or mercerizing agents can be added, if desired, such as ethylene oxide condensation products or cresols. If it is deemed desirable, other known auxiliaries such as lower alcohols can still be added.

As starting substances for the preparation of the alkyl sulfonic acids, containing per one sulfonic acid group at most 7 carbon atoms, saturated aliphatic hydrocar-

bons are appropriate such, for example, as light petrol boiling at 30°-80°C.

According to the present invention at least one sulfonic acid group is introduced into the light petrol, having an average molecular weight of about 60. The sulfonic acid alkali metal salts are prepared from these hydrocarbons advantageously by sulfo-chlorination according to the Reedprocess and subsequent alkaline saponification but also the thioureaprocess of Sprague and Johnson or the method of Johnson and Douglas as well as the oxidation of alkyl sulfides with chlorine can be applied (cf. F. Asinger "Chemie und Technologie der Paraffinkohlenstoffe", (1956) Berlin, pages 395, 423-424). Other methods of introduction of sulfonic acid groups, such as the sulfoxidation can be used.

The lower alkyl dialkanolamine corresponds to the general formula

in which R represents an alkyl radical of 2-5 carbon atoms and m represents a number of 1 to 2 and n is 2 or 3. The alkyl dialkanolamines advantageously should be soluble in water. There may be used, for example, n-propyl-diethanolamine, isoamyl-diethanolamine, ethyl-bis-[2-hydroxy-isopropyl]-amine, n-butyl-bis-[2-hydroxypropyl]-amine or preferably butyl- or isobutylamine which has been reacted with 2-2.5 moles of ethylene oxide.

As phosphoric acid esters which may be added those derived from alcohols, especially alkanols of a medium molecular weight, containing about 4-8 carbon atoms, are preferred, for example trioctylphosphate, in particular tributylphosphate and triisobutylphosphate. These phosphoric acid esters keep their activity even when partially saponified.

The proportion by weight of the alkyl sulfonates to the alkyl dialkanolamines is to be 1:0.3 to 1:5, preferably 1:0.8 to 1:2. The amount of the phosphoric acid ester added is 1-15 percent, referred to the total of the sulfonates and alkyl dialkanolamines, preferably 2-6 percent.

The wetting agent mixtures according to the process of the present invention are soluble in dilute as well as in highly-concentrated alkaline lyes, as they are used, for example, for mercerizing or leaching of cellulose fibres, and even in the cold.

The following Example serves to illustrate the invention but it is not intended to limit it thereto.

EXAMPLE

230 g of a light petrol sulfochloride which was prepared according to the Reed process by sulfo-chlorination of a light petrol (boiling at 30°-80°C and having an average molecular weight of 70) and which contains 16.9 percent of sulfur and 20.9 percent of chlorine and thus has about 6 carbon atoms per one SO_2Cl group was added dropwise within one hour at 50°-60°C into a solution of 104 g of sodium hydroxide in 1 litre of water. After stirring for 1 hour, the reaction is complete. After filtration of some resinous impurities the solution contains 30 percent of sulfonate.

Preparation of the mercerizing agent solution:
70.5 g of the above-mentioned light petrol sulfonate solution (containing 21.2 g of sulfonate) are mixed, while stirring, with 37.5 g of butyldiethanolamine, 26 g of water and 8 g of triisobutylphosphate. The clear solution then contains 42 percent of surface active agent.

This composition of mercerizing wetting agents is clearly soluble in mercerizing baths of 300 g of sodium hydroxide/litre.

The light petrol sulfonate alone (i.e., without additions) soon creams up in these baths, i.e., it is useless.

In the following Table the shrinkage values of the product of the present invention of the Example are given. The Table shows that because of good solubility of the products in strong alkaline baths which product combination is obtained according to the present invention, surprisingly good shrinkage values are also obtained.

in which R is alkyl of 2 to 5 carbon atoms, n is 2 or 3 and m is a number of 1 to 2, and

- c. about 1 to about 15 percent by weight of a phosphoric acid ester of alkanols of 4 to 8 carbon atoms.
- 2. A composition as claimed in claim 1, consisting of
  - a. about 30 to about 55 percent by weight of said sulfonic acid or sulfonate,
  - b. about 40 to about 65 percent by weight of said amine and
  - c. about 2 to about 6 percent by weight of said ester.

Table

Shrinkage values measured in baths of 300 g of sodium hydroxide/litre according to the method given in
"Praktikum der Textilveredlung", Otto Meechels, page 24, (1949),
Springer Verlag, Berlin-Goettingen-Heidelberg

surface active agent/litre	shrinkage (in % at 15°C) after...				
	30 sec.	60 sec.	120 sec.	180 sec.	240 sec.
2.5	6.0	10.8	12.8	13.0	13.2
5.0	8.6	11.6	12.4	13.0	13.5

We claim:

1. Detergent mixture consisting essentially of
  - a. about 10 to about 80 percent by weight of an alkyl sulfonic acid derived from light petrol boiling at 30°-80°C or an alkali metal salt thereof, having on an average one sulfonic acid group per 7 carbon atoms at most or a mixture thereof,
  - b. about 20 to about 85 percent by weight of an amine of the formula

3. A composition as claimed in claim 1, wherein the sulfonic acid is derived from a light petrol having an average molecular weight of about 70.

4. A composition as claimed in claim 1, wherein the amine is butyldiethanolamine.

5. A composition as claimed in claim 1, wherein the ester is triisobutylphosphate.
